Primary Examiner — Elizabeth Albert(74) *Attorney, Agent, or Firm* — Gifford, Krass, Sprinkle, Anderson & Citkowski, P.C.(57) **CLAIM**

The ornamental design for a vase, as shown and described.

DESCRIPTION

FIG. 1 is a perspective view of the vase showing my new design;

FIG. 2 is a side elevational view of FIG. 1;

FIG. 3 is a top plan view of FIG. 1; and,

FIG. 4 is a bottom plan view of FIG. 1.

The broken lines are included to show a feature that forms no part of the claimed design.

1 Claim, 2 Drawing Sheets(56)
